UNITED STATES PATENT OFFICE.

JOSEPH E. CRISP, OF SOMERVILLE, MASSACHUSETTS, ASSIGNOR TO
MARY E. PEIRCE AND SARAH B. CRISP, OF SAME PLACE.

MAIL-BOX COLLECTION AND DELIVERY.

SPECIFICATION forming part of Letters Patent No. 613,560, dated November 1, 1898.

Application filed July 25, 1891. Serial No. 400,690. (No model.)

To all whom it may concern:

Be it known that I, JOSEPH E. CRISP, of Somerville, in the county of Middlesex and State of Massachusetts, have invented certain new and useful Improvements in Mail-Box Collection and Delivery, of which the following specification, with the accompanying drawings, is such a full, clear, and exact description thereof as will enable others skilled in the art to make and use my invention.

The object of this invention is to produce a mail-box which will receive from or deliver to the route-carrier its full capacity of mail-matter, consisting of letters, cards, papers, pamphlets, ordinary - sized packages, &c., and which will at the same time reduce to a minimum the labor of the carrier.

It consists in making the mail-box with doors preferably opposite each other and providing these doors with suitable connecting mechanism, so that mail-matter introduced into the box through either of these doors must be removed from the box through the other of said doors.

It also consists in arranging the operating mechanism so that the principal amount of the time and labor of operating the doors will fall upon the owner of the box, with a corresponding gain to the route-carrier.

In the drawings, Figure 1 is a perspective view of the box having the carrier's door located thereon. Fig. 2 is an inside elevation of the carrier's door, showing the clip for exposing mail to be collected to the carrier's view

and the automatic mechanism operated by said clip for locking said door. Fig. 3 shows details of the key. Fig. 4 is an enlarged sectional elevation of that part of the carrier's door having the lock. Fig. 5 is a perspective

view of the cam and clip for the carrier's door. Fig. 6 is a perspective view of the slide D² and its associate parts. Fig. 7 is a horizontal cross-section of the box on line y y, showing the mechanism by which the owner's door is automatically locked after mail has been deposited by the owner, also showing the key-hole and drain-holes in the bottom of the box.

Fig. 8 is a horizontal cross-section of the lower part of the box on line x x, looking toward the bottom, showing the locking mechanism with both doors closed and locked.

Fig. 9 is a vertical cross-section showing the lock-plate with the owner's key inserted. Fig. 10 is a cross-section showing the carrier's door open with the key in position. Fig. 11 is a like view showing the owner's door opened.

The body of the box A is made with two doorways, preferably upon opposite sides thereof. In these doorways are hung the doors B and C, so that they will swing upon the rods A', and around the rods are the springs A², which close the doors. The rods A' pass up from the bottom of the box through suitable lugs formed upon or attached to the inside of the box, above and below the doorways. The part of the doors which swings outward closes into a rabbet on the box, and the part of the doors which swings inside the box closes against the inside of the box, so that the doors close substantially water-tight, Fig. 11. Should any water pass between the edge of the doorway and the back joint, it passes under the lock-plate and out of the drain-holes A' in the bottom of the box.

Above the door C there is hung a narrow door A³, through which letters or cards may be placed in the box when the doors B and C are both locked, Fig. 1, and a like narrow door is hung on the door B. This door is provided with the lifting-handle A⁴ and is also spring-closed. The doors B and C are glazed, so that the contents of the box can be observed from either side, and should the box be set in a house-door leading into a dark hallway it will be illuminated from the outside.

A plate D forms the bottom of the box, upon which mail-matter rests. This plate is held in position by the rods A', which pass through it. On its under side and to the lower part of the doors B and C is attached the locking and connecting mechanism used for mail-receiving purposes, constructed and operating as follows: In a dovetail guideway D', properly located upon the lock-plate D, there is fitted the slide D². To the slide D² there is secured the piece D³, so that it will engage with the curved arm B', attached to the door B, when said door is closed, Figs. 7 and 9, the contacting parts of the piece D³ and the arm B' being at such an angle that the opening of the door B will move the slide D² to its backward limit of motion, Fig. 10. The rear end

of the slide D² is angular, and when the slide is moved back this angular end will engage with a segmental piece C', attached to the door C, Figs. 8 and 10. The segmental piece 5 C' is formed of two segments of different diameters, joined by the incline C², against which the rear end of the slide D² rests when fully back, and when the door C is opened the incline C² will move the slide D² to its forward limit of motion, Fig. 8, and the segment will hold the door B closed by holding the angular side of the piece D³ fixed against the inclined end of the curved arm B', as shown in Fig. 9 of the drawings.

15 To lock the door B, the slide D² is held at its forward limit of motion by the stationary bolt E, formed in one piece with the back spring E' and secured to the lock-plate at D⁴ by the screw E². This screw holds E and E' 20 in correct line, but leaves them to swing free upon it as the lock is operated. The back spring E' acts upon a detent D⁵, formed upon the piece D³, and the end of the stationary bolt E engages with the abutment D⁶, also 25 formed upon said piece, Figs. 8 and 11. This prevents the backward movement of the slide D² until the stationary bolt E is sprung to register with the recess D⁷, formed in the piece D³, when the door B can be opened and 30 the slide D² moved backward. To move the stationary bolt E into line with the recess D⁷, the swinging cam F is mounted upon the lock-plate at D⁸. This cam has two steps, upon one of which, F', the stationary bolt E rests when its end is opposite the abutment D⁶, Fig. 7, and upon the other, F², when opposite the recess D⁷, Fig. 8. These steps also 35 act as detents to keep the cam F in either of its positions. There is also fixed in the lock-plate the stop-pin F³ to limit the throw of 40 the cam F.

To swing the cam from either step to the other, it is provided with the slot F⁴, into which the web of the owner's key G enters 45 and swings the cam as desired.

When the door B opens into a house or other safe place, the stationary bolt E may be left resting upon the step F² by turning the key G completely around and withdrawing 50 it from the keyhole G', thus leaving the door B free to open at any time except when the door C is open. The keyhole G' is located at the bottom of the box, and the key turns principally upon the spindle G², Figs. 55 8, 9, and 11.

The carrier's door C is locked and unlocked automatically as follows: To the door C is secured the short arm C³, which will just clear the outer end of the slide D² when said slide 60 is at the end of its forward motion, Fig. 11. This short arm is provided with the catch C⁴, which will engage with the spring-bolt D⁹ when the door C is closed by its spring and there lock it. The spring-bolt D⁹ is fitted to 65 the outer end of the slide D², from which it is pressed forward by the spring D¹⁰, and its forward motion is limited by the stop-pin D¹¹,

working in the slot D¹², so that when the slide D² is drawn fully back the spring-bolt D⁹ is just clear of the catch C⁴. The slide D² 70 is in fact a sliding lock-case carrying a spring-bolt, so far as relates to the door C.

Opening the door B automatically withdraws the bolt D⁹ from the catch C⁴, and opening the door C automatically moves the 75 spring-bolt D⁹ into position to lock said door when its spring closes it.

The segmental piece C' is provided with the spring-catch C⁵, which engages with the rear end of the slide D² when the door C is 80 wide open and there holds it.

To keep the door C closed whenever the door B is open, there is hung upon the lock-plate the swinging catch F⁵, whose spring F⁶ 85 throws it into connection with a catch C⁶ formed on the arm C³, Fig. 11. A pin B², properly located upon the curved arm B', contacts with the projection F⁷ of the swinging catch F⁵ and just pushes the catches apart when the door B is fully closed, Figs. 8 and 11. 90

From the foregoing description of the construction and operation it will be seen that the operation of this box for mail delivery is automatic so far as relates to the route-carrier and that while the box is given the largest 95 possible receiving capacity and safety the locking and unlocking of the carrier's door is transferred to the owner of the box, with a saving of the carrier's time.

The action of this box for mail delivery is 100 as follows: The owner with his key unlocks his door and opens it, removing the mail. This moves the sliding lock-case D² and unlocks the carrier's door from the bolt D⁹. The spring A² closes the owner's door, which moves 105 apart the catches F⁵ and C⁶, leaving the carrier's door free to open, with the box empty. The route-carrier by the knob of the door C opens it back so that the catch C⁵ will hold 110 it open, at the same time locking the owner's door B. The carrier deposits the mail within the box and pushes the door C clear of the catch C⁵. The spring A² closes it, and the spring-bolt D⁹ locks it, leaving the mail locked 115 within the box, from which it can only be removed by the use of the owner's key. The whole of the carrier's movements can be performed with the hand holding the mail to be deposited.

When there is mail placed in the box for 120 collection, the doors B and C are locked, so that they can only be opened by the carrier. This is performed automatically by the owner as he places the mail or a portion of it under a clip which holds the mail exposed to the 125 carrier's view, in case he has no mail to deliver, when he passes near the box. For this purpose a lock-bolt H is fitted to slide free in bearings H' and H², formed upon or attached to the inside of the carrier's door C, near the 130 top, Fig. 2. Hung upon one of the rods A' so that it will swing behind the bolt H is the cam H³, which carries the clip H⁴. A spring H⁵ holds the end of the clip against the in-

side of the door C, and when the clip is drawn out to the position shown by Figs. 2, 4, and 5, bolt H is fully shot by the cam II³ and the door C is locked.

5 The doors, it will be seen, may have their mutual interaction changed from the above-described normal operating condition to a condition wherein the locking devices are set to be serially operated by the movement of 10 said doors. They may afterward be returned to normal operating condition. When serially operating, the mere closing of either of the doors unlocks the other, and when one door is opened the other is tightly locked and becomes a closed back for the box.

To prevent the action of centrifugal force from throwing the bolt H out when the door C is closed by its spring, a light spring H⁶ is placed around the bolt H, as shown. 20 A tumbler H⁷, formed from a round pin of two different sizes, is fitted to slide free in the bearing H'. The smaller end of this tumbler rests in the groove H⁸, formed in the bolt H, when said bolt is back, and 25 drops into the hole H⁹ and holds the bolt H firm when it is shot forward, as shown by Fig. 4. The tumbler H⁷ is connected to the sliding pin K by the cross-pin K', which passes through the larger parts of both tumbler and 30 sliding pin, so that the raising of the sliding pin will also raise the lower end of the tumbler out of the hole H⁹ and allow the bolt H to be withdrawn. The sliding pin K is provided with an upper bearing H¹⁰, and around 35 the larger part of the sliding pin, between the bearing H¹⁰ and the cross-pin K', is placed the spring K², which causes the tumbler H⁷ to drop quickly when the bolt H is shot forward.

The keyhole L is made rectangular, its 40 height being from the point of the sliding pin K to the bottom of the incline H¹¹, formed in the bolt H, and its width sufficient to allow the key to give the desired backward movement to the bolt H. The upper part of the 45 bolt H is provided with the incline H¹¹, which is located with reference to the keyhole L, when the bolt is shot, as shown by Fig. 4.

The key is formed of two parts M and M', provided with the handles M². These parts 50 are joined together by and swing around the pin M³, a spring M⁴ and stop-pin M⁶ holding the key ready for use in the position shown by Fig. 3. The part of the key M is made with the bevel-ended stud M⁶ upon it, and 55 the part M' is made with inclined edge M⁷, as shown by Fig. 3, the distance of the stud from the end of the key being such that when the end of the key rests against the bottom of the keyhole the stud M⁶ will register with 60 the lower end of the sliding pin K, the thickness of the parts of the key being such when in this position that the inclined edge M⁷ of the part M' of the key will just meet the commencement of the incline of the bolt H. Pressing together the handles M² causes 65 the stud M⁶ to raise the tumbler and release the bolt H, when the incline M⁷, acting upon

the incline H¹¹, withdraws the bolt H. The key is held in the keyhole by the stud M⁶ and serves as a handle to swing the door C 70 open to the catch C⁵ when the handles are released and the spring M⁴ brings the key to its normal position in the keyhole. The closing of the door C by its spring throws the key from the keyhole, leaving it upon the 75 carrier's chain ready for use in the next box of his route in which there is locked mail for collection.

It will be seen that by varying the length of the stud M⁶ and the angle of its end and 80 making the end of the sliding pin K to coincide therewith these locks can be varied as desired and each route have its master-key which will not be of use on any other. The swinging out of the clip H⁴ also brings a 85 spring-catch N into position to engage with the catch B³, fixed on the door B, as shown by Fig. 7, in this manner.

The spring-catch N is pivoted to a bearing A⁶ by the pin A⁵, and its end N' is extended 90 across the box, so that when the bolt H is shot the outer end of the bolt will swing the catch out, using for a fulcrum the spiral spring N², as will be understood. The hole in the spring-catch N through which the pin 95 A⁵ passes is slightly enlarged or slotted, and when the door B is closed the spring N² gives and the catches N and B³ will engage and lock the door B. When the bolt H is withdrawn by the carrier's key, the spring N², acting 100 against the spring-catch N, with the pin A⁵ as a fulcrum, disengages the catches, and the door B can then be opened by the owner of the box.

From the foregoing it will be seen, first, 105 that the owner's act of throwing the clip-lever H⁴, and thus exposing against the carrier's door mail for collection to the view of the carrier, automatically locks the doors B and C, so that the box can only be opened by 110 the carrier's key; second, that the carrier's act of depositing mail for the owner of the box and thereafter closing his door automatically locks the doors B and C, so that the box can only be opened by the owner's key; third, 115 that the act of the owner unlocking his door and thereafter closing the same without throwing the clip-lever H⁴ automatically unlocks and leaves open the carrier's door ready for another delivery into the box; fourth, 120 that all mail-matter intended for the owner of the box must pass through it in one direction and all mail-matter intended for the carrier must pass through it in the opposite direction; fifth, that the principal amount of 125 time and labor of operating the box falls upon the owner, who will not notice it the few times he has to visit it, and makes a slight saving of time and labor to the carrier per box, which in the aggregate will be considerable. 130

This box may be placed in the most convenient place for the carrier—on a tree or post, in a fence, or in a house-door. In the latter place the rigidity of either door when the

other is open or being opened renders it impossible to pass any injurious matter into the house, which is a valuable feature of this invention, and, wherever placed, the construction of the box renders it substantially weather-proof.

Having thus described my invention, I claim and desire to secure by Letters Patent—

- 10 1. A mail receiving and collecting box provided with serving-doors for the owner and carrier, mutually-interacting locking devices for each of said doors and means whereby the locking devices may be set to be serially operated by the movement of said doors, substantially as described.
- 15 2. A mail receiving and collecting box provided with serving-doors for the owner and carrier, mutually-interacting locking devices
- 20 20 for each of said doors and operated by their serial movement and additional locking devices for the carrier's door and means whereby, when said additional locking device is operated, both doors may be locked and then
- 25 25 returned to normal operating condition by the carrier, substantially as described.
- 30 3. A mail receiving and collecting box, provided with serving-doors for the owner and carrier, mutually-interacting locking devices
- 35 30 for said doors, operated by their serial movement, and additional locking devices for the owner's door which lock said door until returned to normal operating condition by the owner, and leave the carrier's door unlocked substantially as described.
- 40 4. A mail receiving and collecting box provided with swinging doors for the owner and carrier, mutually-interacting locking devices for each of said doors, and additional locking
- 45 40 devices for the carrier's door and means whereby when said additional device is operated, both doors may be locked, and other means whereby when the owner's door is closed, the carrier's door will be unlocked, substantially as described.
- 50 5. In a mail receiving and collecting box, provided with swinging doors for the owner and carrier, the combination of clip H⁴, a locking device and connected mechanism mounted on the carrier's door, and a locking device for the owner's door mounted on one of the sides of the box and which is moved into position to automatically lock the owner's door, when it is closed, after the clip H⁴, has been operated, substantially as described.
- 55 6. In combination with a mail receiving and collecting box with doors for the owner and carrier mounted on opposite sides of the box, whose normal position is closed, a reciprocating slide carrying a spring-operated locking-bolt, a suitable guideway therefor, connecting mechanism between said doors and said slide, substantially as described, to reciprocate said slide in opposite directions as said doors are alternately opened, substantially as shown and described.
- 60 7. In combination with a mail receiving and

collecting box with doors for the owner and carrier mounted on opposite sides of the box whose normal position is closed, the door B, 70 carrying and operating the curved arm B', the door C carrying and operating the segment C', the slide D², and the piece D³, all substantially as described.

8. In combination with a mail receiving and 75 collecting box with doors for the owner and carrier mounted on opposite sides of the box, whose normal position is closed, a reciprocating slide carrying a spring locking-catch, mechanism substantially as described for reciprocating said slide by the opening of said doors, and cam-and-bolt mechanism substantially as described, for allowing or arresting the reciprocation of said slide for the purpose set forth. 80

9. A mail receiving and collecting box with doors for the owner and carrier mounted on opposite sides of the box, whose normal position is closed, locking devices for each of said doors, connecting mechanism between said locking devices and the other of said doors, which is operated at the commencement of the opening of either of said doors to lock the other of said doors and cause such door to form a fixed back to said box when either 95 door is open or being opened, substantially as shown and described.

10. In a mail receiving and collecting box having spring-closed doors for the owner and carrier mounted on opposite sides of the box, 100 whose normal position is closed, locking devices for each of said doors, connecting mechanism substantially as described between said locking devices and the other of said doors, in combination with the spring-catch C⁵ 105 mounted upon the segment C' of the door C and the reciprocating slide D², substantially as and for the purpose set forth.

11. In combination with a mail receiving and collecting box with doors for the owner 110 and carrier mounted on opposite sides of the box, whose normal position is closed, the door B carrying the catch B³, the spring-catch N, mounted upon one of the sides of said box between said doors, and operating mechanism therefor substantially as described mounted upon the door C, all substantially as shown and described. 115

12. In combination with a mail receiving and collecting box having spring-closed doors 120 for the owner and carrier mounted on opposite sides of the box, whose normal position is closed, a bolt for the carrier's door, which is shot through the owner's door, and a combined key and handle for opening said carrier's door formed of two levers pivotally connected and spring-closed, operating substantially as described and for the purpose set forth. 125

13. A mail receiving and collecting box, provided with swing-doors for the owner and carrier, mutually-interacting, locking devices for each of said doors, an additional device for the carrier's door and means whereby 130

when said additional device is operated, both doors may be locked, and other means whereby when the owner's door is closed, the carrier's door will be unlocked.

- 5 14. A mail receiving and collecting box, provided with serving-doors for the owner and carrier, mutually-interacting locking devices for each of said doors, and means whereby the locking devices may be set to a predetermined position, so that the doors may be operated in either one or the other of two modes as described.
- 10 15. A mail receiving and collecting box, pro-

vided with a key-operated door for the owner, and a key-operated door for the carrier, mutually-interacting locking devices for each of said doors, and means substantially as described whereby mail - matter introduced through either of said doors must be removed through the other of said doors, substantially as described.
